BAGGAGE CHECK

Arthur H. Swett, Jr., Verona, N. J., assignor to
American Tag Company, Newark, N. J., a cor-
poration of New Jersey

Original application November 5, 1940, Serial No. 364,423. Divided and this application October 8, 1941, Serial No. 41,952.

3 Claims.

(Cl. 40—20)

In my pending application Serial No. 364,423, of which this present application is a division, there is set forth a tag appliance comprising a piece of stiff sheet material, as cardboard, and a coupling consisting of a strip of stiff elastic material, as wire, rebent midway its length and having its extremities rebent and crossing each other, the coupling being so secured to the piece as to be fast thereto and lie in close relation to the plane thereof. The construction presents these advantages: The appliance can be assembled with others in face to face and hence compact state and the assembling and also the removal from the pack thus formed of any one appliance can readily be performed because the coupling exists as a unit with and in face to face relation to said piece. To attach the appliance to the handle-ring of a satchel or the like requires but a simple thrust-wise effort in which the rebent or hooked extremities of the coupling would be directed toward and cammed apart by the ring so as to catch thereon. The appliance is particularly adapted as a baggage check if, as in all the forms shown in said application, that part of the piece of sheet material to which the coupling is immediately secured is readily separable from the other part of the piece whereby, the two parts being provided with identical identifying data, one part will serve as a receipt to be handed to the owner while the other remains attached by the coupling to the baggage article.

The invention specifically set forth in this my present application contemplates that the appliance shall include, with the said coupling, a check or check proper of stiff sheet material formed with linear weakening so disposed, for substantially its full length, as to divide the check into two sections normally existing connected and in substantially the same plane, the coupling being secured to one section the same as in my said pending application but having its extremities crossing the weakening and, as above, lying close to the plane of the check; as will appear, the said weakening may be bent or straight. The weakening permits the two sections, which may have identifying data, to be separated, leaving one, or the stub, attached by the coupling to the article to be checked and the other to be delivered to the owner of the article as his receipt. The attaching to the baggage article may be effected in the simple manner above indicated, or by a thrustwise effort, and the appliance may exist, as shown by the examples herein presented, with the coupling contained wholly within the area of the check, whereby when assembled with others

to form a pack all sides of the pack will be clear of projections.

projections.
In the drawing

Fig. 1 is a front elevation of one form of a check appliance embodying the present invention.

Figs. 2 and 3 are similar elevations of two ether forms; and

Fig. 4 is a fragmentary side elevation of the form shown in Fig. 1, with the coupling and the portion of the check to which it is immediately clamped displaced from the initial state shown by Fig. 1.

Referring, first, to the form shown in Figs. 1 and 4; A piece of stiff sheet material, as cardboard, forms the check or check proper 1, being linearly weakened here by an arcuate slit 2 whose termini are directed toward and are adjacent one of the margins of the check, being here shown, 20 though not necessarily, enlarged to form holes 2a. The section or tab 1a (which forms the stub of the check) thus partially circumscribed by the weakening may be bent out of the plane of the section 1b of the check, forming the customer's receipt, thereupon to be torn therefrom, as will appear. The coupling is a stiff elastic strip, as wire, rebent at 3 and having its extremities 4 diverging and their terminals themselves rebent to 25 form hooks and crossing and in close-lying relation to each other. The coupling exists with its extremities 4 penetrating a slot 1x in the tab 1a. With said extremities thus penetrating the tab or stub the coupling is then bent so as to clamp the stub between the portion of the coupling including the rebend 3 and the portions of said 30 extremities which are at the opposite face of the check, leaving the latter portions crossing the linear weakening 2 and in close-lying relation to the check. Whereas said extremities cross the 35 weakening said rebent 3 should lie, as shown, wholly within the area of the stub.

The unit formed by the stub and coupling may be torn away from the rest of the appliance (receipt 1b) and then attached to the baggage in the way indicated, the receipt being surrendered to the customer; or of course the attaching may be first effected and then the receipt torn away.

In the form thus described the stub and receipt may bear duplicated identifying data such as is shown at 7, for instance, in Figs. 2 and 3.

In Fig. 2 the construction is essentially the same as already described except that the linear weakening, a slit 6, is of rectangular form, developing a long tongue-like stub 1c. The duplicated indicia are shown at 7.

In Fig. 3 the check 8 is traversed from one to the other side margin by a line of perforations, or it may be scoring, forming the linear weakening 9 and dividing the check into two sections 8a and 8b bearing the duplicated indicia 1. The coupling 10, formed the same as already described, penetrates one section, as the stub 8a, near the weakening, and extends across the latter into close-lying relation to the other section 8b, forming the customer's receipt. The clamping of the stub by the coupling is the same as already described.

Because the coupling is in rigid and in face-to-face relation to the check and crosses the linear weakening it incidentally serves as a reinforce or so as to aid in preserving the check in its normally flat state, particularly against inadvertent bending of the stub out of the plane of the customer's receipt.

By the construction shown by Fig. 1, when the owner retrieves the baggage article only an inconspicuous part of the check proper remains attached to the article and it will also appear mutilated so that the appliance cannot be resold by the porter or other agent. In the forms shown by Figs. 2 and 3, the owner can readily tear the

stub away from the coupling, thus to accomplish the same purposes.

Having thus fully described my invention, what I claim is:

- 5 1. In a check appliance, the combination of a check formed of stiff sheet material having two sections, each bounded in part by a common linear weakening, said sections normally existing maintained in substantially the same plane, and a coupling consisting of a stiff elastic strip having a rebend and having both extremities penetrating one section and the rebend at one face and portions of said extremities at the other face of said section and said rebend and portions co-acting to clamp said section, said extremities crossing said weakening and lying close to the plane of the check and having their terminals themselves rebent and crossing each other.
- 15 2. The combination set forth in claim 1 characterized by said weakening existing crooked and having its terminals each adjacent a margin of the check.
- 20 3. The combination set forth in claim 1 characterized by said weakening extending generally straight across the check.

ARTHUR H. SWETT, JR.
